UNITED STATES PATENT OFFICE.

ADOLPH WUNDER, OF NEW HAVEN, CONNECTICUT, ASSIGNOR TO SARGENT & CO., OF SAME PLACE.

DESIGN FOR A BIRD-CAGE HOOK.

Specification forming part of Design No. 5,634, dated March 5, 1872.

To all whom it may concern:

Be it known that I, ADOLPH WUNDER, of New Haven, in the county of New Haven and State of Connecticut, have invented a new Design for Bird-Cage Hook; and I do hereby declare the following, when taken in connection with the accompanying drawing and the letters of reference marked thereon, to be a full, clear, and exact description of the same, and which said drawing constitutes part of this specification, and represents, in—

This invention relates to a design for the article of manufacture known to the trade as a "bird-cage hook"—that is to say, a hook or bracket-arm from which bird-cages or other articles may be suspended; and it consists in the peculiar configuration of the bracket and base, as shown in the accompanying illustration, separately or together.

The configuration of the base, which is constructed to give support to the bracket both vertically and transversely, is shown in Fig. 2, and its surface may be ornamented in any desirable manner. The arm or bracket extends from the base outward, terminating in the form of a hook, its connection with the bracket being at two points, and the configuration of the bracket is clearly shown in Fig. 1.

This bracket may be used upon a different base, or a different bracket upon this base, hence I do not confine myself to the combination of the two.

I claim as my invention—

The design for bird-cage hook or bracket and base, separately or together, as shown in the accompanying illustration, and as herein described.

ADOLPH WUNDER.
